UNITED STATES PATENT OFFICE.

EDMUND NOLAN AND CHARLES W. WALTERS, OF DETROIT, MICHIGAN.

GREASE-GUN FILLER.

Application filed April 20, 1921. Serial No. 463,097.

To all whom it may concern:

Be it known that we, EDMUND NOLAN and CHARLES W. WALTERS, both citizens of the United States of America, residing at Detroit, in the county of Wayne and State of Michigan, have invented certain new and useful Improvements in Grease-Gun Fillers, of which the following is a specification, reference being had therein to the accompanying drawings.

This invention relates to grease gun fillers, and it is the object of the invention to provide a device that will quickly introduce a compact mass of grease into a grease gun eliminating any air spaces in said mass.

A preferred embodiment of the invention is hereinafter described and is illustrated in the accompanying drawing wherein:

Figure 1 is a view of the grease gun filler in side elevation;

Figure 2 is a similar view showing the pivotally connected complementary barrel members swung apart for filling;

Figure 3 is a top view of the parts as shown in Figure 1.

In these views the reference characters A and A' designate a pair of complementary semi-cylindrical members forming a barrel adapted to be filled with grease. The member A is formed at its upper end with a pair of diametrically opposed lugs B embracing the corresponding end of the member A' and pivotally connected to the latter as indicated at C. The member A is formed with an integral upward extension D, the upper end of which is bent through substantially right angle to form a handle E. The member A' is likewise formed with an integral upward extension, the lower portion F of which extends at an upward inclination across the axis of the barrel A, A', said extension terminating in a handle G below and spaced from the handle E. Within the barrel A, A' a piston H is adapted to reciprocate, said piston being secured to the lower end of a rod I having guiding engagement with the part F, and having at its upper end an actuating knob or head J. A spring K coiled upon the rod I is compressed between the head J and part F during the latter portion of the downward stroke of said rod and functions to maintain the rod and piston normally partially raised.

In the use of the described device, after the rod I and piston H have been adjusted

to their upper limiting position shown in Figure 1, the operator by means of the handles E and G swings the barrel members A, A' to their divergent positions shown in Figure 2. The barrel of the device is then thrust into a mass of grease so that the latter enters and substantially fills the barrel. The handle members E and G are then firmly gripped to adjust them into proximity and to shift the members A and A' into their parallel and abutting relation shown in Figure 1. The grease between said members is thus subjected to a compression, the effect of which is to eliminate any air spaces, and to insure retention within the barrel of its contents when the device is withdrawn from the mass of grease. Pressure is now applied to the knob J by the thumb of the hand which is gripping the handles E and G and the piston H is thus actuated to the lower portion of the barrel, extruding the grease which may be received by a grease gun, grease cup, or any desired receptacle.

It is a highly desirable feature of the invention that the grease is allowed to freely enter the barrel when the latter is initially introduced into the mass of grease, the divergent relation of the barrel members permitting a ready displacement of air which otherwise would be trapped between the entering grease and the piston and resist complete filling of the barrel. Also elimination of any air spaces in the mass of grease is fully assured, first, by the compression to which the contents of the barrel are subjected when the parts A, A' are adjusted from a divergent to a parallel relation, and second, by the pressure to which the mass is subjected during ejection by the piston H. It is to be observed that the handles G and E are so arranged as to be conveniently gripped and pressed toward each other by one hand of the operator, the piston H being operable by the thumb of the same hand, while the other hand is free to hold the grease gun or grease cup which is to be filled.

What we claim as our invention is:

1. In a device of the character described, the combination with a receptacle comprising a pair of complementary pivotally connected members forming a barrel, of handles carried by said members for relatively adjusting the same angularly, a piston reciprocatory in said barrel, actuating means for

said piston having guiding engagement with one of said members and resilient means for normally maintaining said actuating means in a predetermined position.

5. 2. In a device of the character described, the combination with a pair of complementary pivotally connected members forming a barrel, of integral extensions from said members at one end of the barrel terminally

10 forming handles for relatively adjusting said members, a piston reciprocatory within said barrel, a rod for actuating said piston having guiding engagement with one of said extensions and elastic means for normally maintaining said piston in a predetermined position.

15 3. In a device of the character described, the combination with a pair of complementary barrel forming members pivotally connected at one end of the barrel, of handles for said members at said end of the barrel; a piston reciprocatory within the barrel, actuating means for said piston having guiding engagement with one of said members

20 and a resilient element for normally holding said piston in a predetermined position.

25 4. In a device of the character described, the combination with a pair of complementary barrel forming members pivotally connected at one end of the barrel, of a piston reciprocatory within said barrel, an actuating

30 rod for said piston, and handle forming extensions from said members at said end of the barrel, one of said extensions having a portion crossing the axis of the barrel and forming a slide guide for said rod.

35 5. In a device of the character described, the combination with a pair of complementary pivotally connected barrel forming members, of a piston reciprocatory within

40 said members, an actuating rod for said piston projecting beyond one end of said members, handle forming extensions from said members one of which has a portion forming a slide guide for said rod, and a spring coiled upon said rod and abutting against said extension tending to retract the piston.

45 6. In a device of the character described, the combination with a pair of complementary barrel forming members pivotally connected at one end of the barrel, of a pair of integral extensions from said members at said end of the barrel terminally and adjacently bent to jointly form a handle grip, a piston slidably mounted within said barrel forming members, actuating means for moving said piston forward, and means for automatically returning said piston to its original position.

50 7. In a device of the character described, the combination with a pair of complementary pivotally connected barrel forming members, of a piston reciprocatory within said members, and extensions from one end of said barrel forming members provided at their extremity with portions transverse to the axis of said barrel forming a gripping portion for the device.

55 8. In a device of the character described, the combination with a pair of complementary barrel forming members pivotally connected at one end of the barrel, of a pair of integral extensions at one end of said members terminally bent to form parallel gripping portions in a plane transverse to the axis of said barrel.

60 In testimony whereof we affix our signatures.

EDMUND NOLAN.
CHARLES W. WALTERS.
